ELECTRON DISCHARGE DEVICE

Browder J. Thompson, Basking Ridge, N. J., assignor, by mesne assignments, to Radio Corporation of America, New York, N. Y., a corporation of Delaware

Application November 27, 1936, Serial No. 113,006

10 Claims. (Cl. 250—27)

My invention relates to electron discharge devices, more particularly to grid controlled gas tubes.

In the conventional grid vacuum tubes provided with a thermionic cathode, control grid and anode, the space charge which builds up around the cathode makes necessary the use of comparatively high voltages, such as 100 volts or more, for obtaining current sufficiently large for practical purposes. It is also necessary to use comparatively large grid voltage swings to produce usable variations in the output of the tube. Thus, in the conventional high vacuum tubes comparatively large transconductances are not easily obtainable nor can large anode currents be obtained with small anode voltages. It has been recognized that by introducing a gas in a tube and ionizing the gas the space charge around the cathode could be neutralized and thus large anode currents obtained with the usual anode voltages. However, in the conventional grid controlled tube containing gas, ionization of the gas causes the control grid to lose its control of the electron stream so that while initiation of ionization can be controlled the current cannot be controlled by the control electrode after ionization takes place. Furthermore, in these types of tubes comparatively high voltages, much above ionization voltages, are applied between the anode and cathode to cause a gas discharge between the anode and the cathode. Thus while comparatively high currents can be obtained the loss of grid control and the necessity for high anode-cathode voltages limits the application of this type of tube and prevents its use in conventional radio circuits.

It is, therefore, the principal object of my invention to provide an electron discharge device having a high transconductance and in which large anode currents can be obtained with very small anode voltages and small grid voltage swings. More specifically it is an object of my invention to provide such a tube dependent upon gas ionization for its operation but which nevertheless can be continuously grid controlled.

In accordance with my invention I produce such a tube by introducing gas at a low pressure into an envelope containing the electrodes and ionizing only the space adjacent the cathode to neutralize the space charge and thus make available a large number of electrons. I can then apply only a very small voltage of the order of 2 to 10 volts considerably below ionizing voltage between the anode and cathode to obtain a comparatively large anode current. The flow

of electrons from the cathode to the anode can then be continuously controlled by a grid to which is applied comparatively small voltage swings, inasmuch as there is no gaseous discharge between the main cathode and anode. 5 To produce the ionization of the gas around the cathode I may employ an auxiliary cathode and establish a discharge between the auxiliary cathode and the main cathode, although the same results could be accomplished by establishing a discharge between the auxiliary cathode and another electrode, the main cathode being positioned within the vicinity of the discharge path. In order to confine the ions to the space around the main cathode, which is desirable, 10 I surround the main cathode with a cage having foraminous portions through which the electrons may move and connect the cage to the main cathode. In one preferred embodiment of my invention the auxiliary cathode and the main 15 cathode may be placed within the cage and the control grid in an opening in the cage. In another arrangement the auxiliary cathode alone or with the control electrode may be placed outside of the cage. By the above arrangements 20 while the electrons can reach the anode, the ions are confined to the space around the cathode and are prevented from causing a complete 25 ionization of the gas within the tube or of combining at the surfaces of the other electrodes 30 or on the tube envelope wall and thus losing their neutralizing ability.

The novel features which I believe to be characteristic of my invention are set forth with particularity in the appended claims, but the invention itself will best be understood by reference to the following description taken in connection with the accompanying drawing in which Figure 1 is a schematic diagram of a tube embodying one form of my invention and associated circuit, Figure 2 is a schematic view of a modification of the tube shown in Figure 1 and its associated circuit, and Figure 3 is a schematic view of a still further modification of the tube shown in Figure 1.

In Figure 1 the envelope 10 which may contain a gas for example at a low pressure has mounted within it the main thermionic cathode 11, preferably a filament, and an auxiliary cathode 12. During operation a gaseous discharge is established between these two electrodes to provide ions in the space particularly around the cathode 11. Surrounding the cathodes 11 and 12 is a conducting cage member having the bottom portion 13, preferably of solid 45

sheet material, electrically connected to one of the legs of the cathode filament 11 and provided with insulating bushings 14, 15 and 16 through which the other leg of cathode 11 and the lead 5 for the cathode 12 extend. The remainder of the cage preferably comprises a screen 17 having at its upper side an opening at the edge of which is supported an insulating ring 18. This insulating ring 18 in turn supports the control 10 grid 19 in the opening to completely enclose the cathodes. An anode 20 is supported opposite the grid 19. The cathode filaments are heated from the source of voltage 21 and 22 and cathode 11 maintained at positive potential with respect to cathode 12 by means of voltage supply 23, the 15 value of which is sufficiently high to provide a gaseous discharge between cathodes 11 and 12 to ionize the space around the cathodes. The input circuit voltage is supplied from a source 20 24 between the control grid 19 and the cathode 11, the grid being negatively biased by means of battery 25. The output circuit includes a load 26 connected to the output of anode 20, the load voltage being supplied by means of source of low 25 voltage 27 which is preferably less than that necessary to establish ionization between the cathodes and anode 20. Because the ions generated within the cage cannot leave the cage, only the space within the cage is ionized. The 30 ions, therefore, are used only to neutralize the space charge around the cathodes, permitting a copious flow of electrons to the anode. Since only electrons leave this cage to anode 20 and no appreciable ionization takes place between 35 grid and anode the control grid 19 maintains control over the flow of electrons from the cathodes 11 and 12 to the anode 20. There is thus no loss of ions by recombination at surfaces of, for example, the anode and the walls of the tube 40 and a very efficient tube is thereby produced having a high mutual conductance and a low anode drop. Very small positive voltages on the grid permit large numbers of electrons to move to the anode, since large numbers of electrons 45 released by ionization are close to the grid in the ionized space within the cage.

The gas which may be used within the envelope 50 may be of any of the inert gases, such as neon, helium or argon, or caesium vapor alone or in combination with any of the gases mentioned at relatively low pressures. However, the range of pressure is not critical and may vary from .01 of a micron to 200 microns or more. When using helium I have found that a voltage of approximately 30 volts between the cathodes is sufficient to produce ionization and that a voltage from 2 to 10 volts between the main cathode and the anode is satisfactory in the load circuit. With this arrangement very small grid voltages and 60 currents of a few milliamperes will control large anode currents of the order of 1 or 2 amperes. Such tubes can be directly connected to loud speakers.

To further increase the ion life, the modification 65 shown in Figure 2 may be employed. The envelope 30 contains the main cathode 31 surrounded by cage 33, which is electrically connected to one of the legs of the cathode filament 31 and insulated from the other by bushing 32. Insulating bushings 32 and 32' may be provided to 70 insulate the cathode leads outside of the cage and thus prevent discharge between these legs and the auxiliary cathode. The cage has on one side an opening 34 covered with mesh and at the 75 top an opening for the control grid 35 supported

in an insulating ring 36 in the opening in the cage. The auxiliary cathode 37 may be mounted outside of the cage in front of the opening 34, the source of voltages 38 and 39 providing the heating current and the source of voltage 40 providing the voltage necessary for producing a gaseous discharge between the two cathodes. The cathode 37 is preferably placed close to the shield 33 so that the electrons do not attain sufficient velocity to cause ionization of the gas outside the cage. The input voltage is applied from the source 41 between the grid 35 and the main cathode 31. A grid biasing battery 42 may be used. The anode 43 is connected to the load 44 and the source of anode voltage 45 of a value considerably less than 15 necessary to cause ionization between cathode and anode.

In Figure 3 I show a form of electron current multiplier making use of my invention. Here the envelope 53 contains the thermionic cathode 51 surrounded by a cage 52 electrically connected to one of the legs of the cathode. The other leg is insulated by means of the insulating sleeve 55 which with the insulating sleeve 56 also protects the cathode leads extending outside of the cage 25 to prevent undesirable discharges between these leads and other electrodes within the tube. This cage may be provided with foraminous portions 53 and 54 or openings covered with mesh material through which electrons may pass. An auxiliary cathode 57 is mounted outside of the cage and close to the foraminous portion 53. A control grid 58 is provided between the cage 57 and the foraminous portion 53. An output anode 59 is positioned opposite the other foraminous portion 54. The heating voltages for the cathodes 51 and 57 are furnished by the voltage suppliers 60 and 61, the cathode 51 being maintained at a higher potential with respect to the cathode 57 by means of the source of voltage 62 which has 40 a value at least as great as that necessary to produce ionization between the two cathodes. An input circuit 63 is connected between the control grid 58 and the main cathode 51. The output circuit connected to the anode 59 includes the load 45 64 and the anode voltage supply 65 which is less than that necessary to produce ionization between the cathodes and the anode.

In operation of the tube when a voltage is applied to the grid 58 so that electrons move from the cathode 57 to cathode 51 to ionize the space around the cathode 51 electrons in proportion are released from the space around the cathode 51 and pass through the foraminous portion 54 of the cage to the anode 59. The degree of ionization and hence the number of electrons from the cathode 51 to anode 59 is dependent upon the voltage applied to the control grid 58, that is the higher the voltage on control grid 58 the greater the ionization in the space surrounding the cathode 51 and the larger the number of electrons moving to the anode 59.

While I have indicated the preferred embodiments of my invention of which I am now aware and have also indicated only one specific application for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims.

What I claim as new is:

1. An electron discharge device having an en- 75

veloped containing a gas at a low pressure, a thermionic cathode electrode within said envelope for emitting electrons, a cage surrounding the thermionic cathode and electrically connected to said cathode and having openings through which electrons can pass, an anode electrode for receiving electrons from said cathode electrode, a second cathode for supplying electrons to ionize only the space surrounding said thermionic cathode, means for applying a voltage above ionization voltage between said second cathode and one of said other electrodes, a grid insulatingly supported within the opening in the cage for continuously controlling the flow of electrons to said anode, an input circuit connected between said thermionic cathode electrode and said grid, and an output circuit connected between said thermionic cathode electrode and said anode electrode and including a source of voltage substantially less than that required to produce a gaseous discharge between said thermionic cathode electrode and said anode electrode.

2. An electron discharge device having an envelope containing a gas at a low pressure, a thermionic cathode within said envelope for emitting electrons, a second thermionic cathode within said envelope cooperating with said first thermionic cathode during operation of the electron discharge device for producing ions in the space surrounding said first thermionic cathode, an anode for receiving electrons from said cathodes and means within said envelope and positioned between the cathodes for controlling the discharge from the second thermionic cathode to said first thermionic cathode to control the ionization around said first thermionic cathode, and the flow of electrons to said anode.

3. An electron discharge device having an envelope containing a gas at a low pressure, a thermionic cathode within said envelope for emitting electrons, a second cathode within said envelope cooperating with said thermionic cathode during operation of said electron discharge device for producing ionization in the space surrounding said thermionic cathode, a conducting cage surrounding said cathodes and electrically connected to the thermionic cathode and having foraminous portions through which electrons can pass, an anode outside said cage for receiving electrons from said thermionic cathode, and a control grid insulatingly supported by said cage for controlling the flow of electrons from said thermionic cathode to said anode.

4. An electron discharge device having an envelope containing a gas at a low pressure, a thermionic cathode within said envelope for emitting electrons, a conducting cage surrounding and electrically connected to said cathode and having foraminous portions through which electrons can pass, a second cathode within said envelope and a source of voltage connected between said cathodes high enough to cause ionization in the space between said cathodes, an anode outside of said cage for receiving electrons from said thermionic cathode, an output circuit connected between said anode and said cathode and including a source of voltage lower than that necessary to produce ionization between said anode and cathode, and a control grid for controlling the flow of electrons from said thermionic cathode to said anode, and an input circuit connected between said control grid and said thermionic cathode.

5. An electron discharge device having an envelope containing a gas, a thermionic cathode within said envelope, a conducting cage surround-

ing and electrically connected to said cathode, an opening in said cage, a control grid insulatingly supported in said opening to close said opening, an anode opposite said opening and means for producing ionization within said cage to neutralize any space charge around said cathode when said tube is in operation.

6. An electron discharge device having an envelope containing a gas, a thermionic cathode within said envelope for furnishing electrons, a cage surrounding and electrically connected to said cathode, an opening in said cage, a grid insulatingly supported in said opening to close said opening, an anode opposite said opening for receiving electrons from said cathode, and a second cathode within said envelope.

7. An electron discharge device having an envelope containing a gas, a pair of spaced thermionic cathodes within said envelope, a metallic cage surrounding said cathodes, said cage being electrically connected to one of said cathodes, an opening in said cage, a control grid means for insulatingly supporting the control grid within said opening to close said opening and an anode positioned opposite said opening outside of said cage.

8. An electron discharge device having an envelope containing a gas at a low pressure, a thermionic cathode within said envelope, a metallic cage surrounding said cathode and connected to said cathode and having an opening therein and a control electrode insulatingly supported within said opening to close said opening, and an anode opposite said opening and outside of said cage, and a second cathode within said cage, means for applying a voltage between said cathodes sufficient to ionize the gas surrounding said cathodes, and other means for applying a voltage between said cathodes within said cage and said anode for producing a flow of electrons from the space within said cage to said anode, and an input circuit connected between said control electrode and said cathodes.

9. An electron discharge device having an envelope containing a gas at a low pressure, a thermionic cathode within said envelope for emitting electrons, a conducting cage surrounding and electrically connected to said cathode and having foraminous portions through which electrons can pass, a second cathode within said envelope outside of said cage and opposite one of said foraminous portions, and a grid positioned between said second cathode and the foraminous portion of said cage, and an anode outside of said cage opposite another of said foraminous portions of said cage.

10. An electron discharge device having an envelope containing a gas at a low pressure, a thermionic cathode within said envelope for emitting electrons, a conducting cage surrounding said cathode and electrically connected to said cathode and provided with foraminous portions through which electrons can pass, a second cathode within said envelope cooperating with the thermionic cathode during operation of the electron discharge device for producing ions in the space surrounding said thermionic cathode, an anode positioned on the outside of said cage and positioned opposite a foraminous portion for receiving electrons from the space surrounding the thermionic cathode, and a control grid for controlling the discharge between the thermionic cathode and the anode.
